H. MENTEN,
COMBINED STRETCHER, COT, AND HAMMOCK,
APPLICATION FILED APR. 30, 1912.

1,151,495.

Patented Aug. 24, 1915.

UNITED STATES PATENT OFFICE.

HERMAN MENTEN, OF ASTORIA, NEW YORK.

COMBINED STRETCHER, COT, AND HAMMOCK.

1,151,495.

Specification of Letters Patent. Patented Aug. 24, 1915.

Application filed April 30, 1912. Serial No. 694,296.

To all whom it may concern:

Be it known that I, HERMAN MENTEN, a citizen of the United States, residing at Astoria, Long Island, New York, have invented certain new and useful Improvements in Combined Stretchers, Cots, and Hammocks, of which the following is a specification.

This invention relates to a combined 10 stretcher, cot and hammock and has for its object the provision of a single structure so designed that it may be folded into a small compact bundle for convenience in transportation and when opened out may be converted into a strong and serviceable cot, 15 hammock or stretcher as desired.

In the accompanying drawings I have illustrated a preferred embodiment of my invention and as here shown my invention 20 consists of certain improvements and additions to the combined cot and hammock shown in my prior Patent No. 928,317 granted July 20, 1909, whereby that structure is adapted also for use as a stretcher.

It is to be understood however that my invention is not limited to the details of construction herein disclosed but covers all such modifications thereof as fall within the scope of the appended claim.

In the said drawings: Figure 1 is a perspective view showing the device adjusted for use as a hammock, Fig. 2 is a similar view showing the device in use as a stretcher, Fig. 3 is a similar view showing the device 30 set up for use as a cot, Fig. 4 is a similar view showing the device partially folded, Fig. 5 is a side view of the leg structure collapsed for bundling and Figs. 6 and 7 are detail views which will be hereinafter 35 referred to.

Referring now to the drawings, in which like reference characters indicate like parts throughout the several views, 1 indicates a sheet, preferably of heavy duck, which supports the occupant of the structure. The sheet 1 is hemmed along its side edges to form loops for receiving the ropes 2 and rods 3. The ropes are continuous from one end to the other of the sheet but the rods are 45 formed in three pieces so that when the structure is folded for bundling in the manner shown in Fig. 4, the length of the bundle will be only one third the length of the device when in use.

The rod sections are carried by the ropes in a manner which will be later described,

and when the structure is used as a cot or a stretcher the ends of the rod sections are brought together to form in effect continuous side rods, but when the structure is used as a hammock the rod sections are left unconnected so that the ropes support the entire structure.

One of the principal objects of the present invention is to improve on the side rod and 60 rope construction shown in my prior patent and to provide suitable locking devices between the rod sections so that the entire weight of the structure and occupant may be supported from the ends of the rods and 65 the structure used as a stretcher as shown in Fig. 2.

Beginning at the end of one of the side ropes it will be noted that its free end forms a loop 4 adjacent the end edge of the sheet. 70 The rope then passes through a hole in the rod section and extends along the lower side thereof in a groove 5 provided for the purpose and extending to a point near the opposite end of the rod section, at which point 75 a hole is bored through the rod to its top surface. From this hole 6 the rope passes through a similar hole in the middle rod section adjacent its end. Between the holes 6 the rope lies in grooves in the top surface 80 of the rod sections so that its surface is flush with the surface of the rods. The rope extends along the bottom of the middle rod section in a suitable groove to a point adjacent its other end where it forms a similar 85 joint with the other end section of the rod, thence along the under side of that section to its outer end where the end of the rope is formed into another loop 4 in the manner described. The loops 4 provide attachments 90 for the supporting ropes 21 when the structure is used as a hammock.

The abutting ends of the rod sections are adapted to be connected by pins 8 on one section of each joint fitting a corresponding hole in the other section, the length of the pins being such however, that the slack in the rope over the joint will permit the parts being disengaged in the manner shown in Fig. 6 when the structure is to be used as 105 a hammock.

In order for the structure to be used as a stretcher it is, as stated, essential that the joints between the rod sections be rendered perfectly rigid and to this end I have provided the construction shown in detail in Figs. 6 and 7. Adjacent each joint in the

side rods a short length of brass tube 9 is provided having a sliding fit on one of the rod sections and near one end of the tube a hole 10 is formed with which a catch 11 on the adjacent rod section coöperates when the tube is slipped over the joint, thereby preventing accidental displacement of the tube. As the ropes 2 are flush throughout with the surface of the rods the tubes 9 can have a snug fit on the rods thereby preventing any lost motion in the joints and taking all the strain off of the pins 8. To permit the tubes 9 to be adjusted as described, the side edges of the sheet are cut away a short distance on each side of the joints as shown at 12. To provide grips for the attendants when the device is used as a stretcher the side rods are prolonged beyond the loops 4 a suitable distance as shown at 13.

20 It is desirable when the device is used as a hamimock or a stretcher to maintain the side rods spaced apart and for this purpose I provide end pieces 14 having rings in their ends which slip over the ends of the side rods 3. The end edges of the sheet may be attached to these pieces if desired by suitable hooks as shown.

In order to support the structure when it is used as a cot I provide a set of folding 30 legs 16 similar to those shown in my former patent, the said legs being provided at their upper ends with knobs over which rings 15 attached to the sheet and side rods along each side, engage. When the structure is

used as a cot it is not necessary that the 35 joints in the side rods be secured by the tubes 9 for the reason that each rod section is separately supported on the leg structure thereby holding the pins 8 in their sockets.

My improved structure is especially 40 adapted for army use. When the troops are *en route* on the naval vessels or transports the structures constitute sleeping hammocks. In camp the same equipment serve as comfortable cots and furthermore each 45 soldier has always at hand a serviceable stretcher ready for use whenever needed.

Having thus described my invention what I claim as new and desire to secure by Letters Patent is:

In a device of the class described, the combination of a sheet, side rods in sections extending along the side edges of said sheet, ropes to which said sections are attached, said ropes extending along the upper side of 55 said rod sections at their adjacent ends and then passing through holes in said sections at points a short distance removed from said ends and extending along the underside of said sections between said holes.

In testimony whereof, I have signed my name to this specification in the presence of two subscribing witnesses, this 17th day of April 1912.

HERMAN MENTEN.

Witnesses:
